UNITED STATES PATENT OFFICE.

CLYDE S. PELTON, OF AKRON, OHIO.

MOTOR-CAR HEATER.

1,148,617.

Specification of Letters Patent. Patented Aug. 3, 1915.

Application filed April 29, 1910. Serial No. 558,458.

To all whom it may concern:

Be it known that I, CLYDE S. PELTON, a citizen of the United States, residing at Akron, in the county of Summit and State of Ohio, have invented a certain new and useful Improvement in Motor-Car Heaters, of which the following is a full, clear, and exact description, reference being had to the accompanying drawings.

10 This invention relates to heaters, and more especially to heaters of the combined radiator and register type which are especially adapted for the purpose of utilizing the exhaust from engines of motor vehicles 15 for the purpose of heating such vehicles.

Among the objects of my invention are the provision of a heater of this type which is simple of construction, extremely efficient in operation, and which possesses marked 20 adaptability for the uses for which it is designed.

The invention may be further and generally described as consisting of the combinations of elements embodied in the claims 25 hereto annexed and illustrated in the drawings forming a part thereof, wherein,

Figure 1 shows a plan view of a heater constructed in accordance with my invention and showing the connections between the 30 same and the supply pipe; Fig. 2 represents a transverse sectional view on the line 2—2 of Fig. 1 looking in the direction of the arrows; Fig. 3 represents an end elevation of the heater shown in Fig. 1, the position of 35 the flexible pipe 14 being indicated by dotted lines; Fig. 4 is a horizontal sectional view corresponding to the line 4—4 of Fig. 2 and looking in the direction of the arrows; Fig. 5 is a detail of the bottom of the casing 40 in which the heater proper is located; Fig. 6 is a longitudinal sectional detail of the valve casing corresponding to the line 6—6 of Fig. 7 and looking in the direction of the arrows; Fig. 7 is a transverse sectional view corresponding to the line 7—7 of Fig. 6 and looking in the direction of the arrows; Fig. 8 is 45 a side elevation of the valve and casing shown in the preceding figure, the pipe being omitted; Fig. 9 is a detail in perspective of the elbow connecting the heater proper with its supply; Fig. 10 is a view, partly in elevation and partly in section, of the flexible portion of the heater supply pipe; and Fig. 11 is an end elevation of the heater cas-

ing. Fig. 12 is a plan view of the heater 55 illustrating the mode of reversing the same upon opposite sides of the exhaust pipe.

My invention, as shown herein, is designed especially for use with motor vehicles and will be described in connection with such 60 accessories as will identify it with this art. Certain features of the invention, however, are capable of more general application.

Describing the parts shown herein by reference characters, 1 denotes a fluid supply 65 pipe which, in the embodiment disclosed herein, is preferably the exhaust pipe from the engine of a motor vehicle. The exhaust from the engine is presumed to be supplied through this pipe in the direction indicated 70 by the arrows in Figs. 1 and 3, and, as the engine is generally located at the front of such vehicles, the terms "front" and "rear" will be applied correspondingly in connection with the drawings. In Fig. 1, the upper 75 end of the pipe 1 would be the "front" end of the same, and in Fig. 3 the left hand end of the pipe would be the "rear" of the same. This pipe passes through what, for convenience of description, may be designated a 80 valve casing. This valve casing comprises a pair of bearings, each comprising a semi-circular clip 2 having ears 3 by which it is bolted to a base 4, said base having a semi-circular seat formed therein, as shown at 5, 85 for the adjacent portion of the supply pipe. The base 4 extends longitudinally of the pipe 1 and has the clips 2 secured to the opposite ends thereof. The open side of this base is closed by means of a plate 6, which 90 plate may be conveniently held in place by the same bolts 7 which unite the clips to the base, and this plate carries an elbow 8 projecting therefrom with one branch substantially parallel with the pipe 1. The pipe 1 is 95 provided with an aperture in the side thereof which is presented toward the elbow 8, the position of the pipe being shown in dotted lines in Figs. 6 and 7 and the edge of the recess in said pipe being indicated at 9. 100 This recess extends inwardly from the side of the pipe adjacent to the elbow 8 about as far as the longitudinal axis of the pipe.

10 denotes a damper or valve projection which is carried by a plate 10* mounted on 105 a stud 11 located at one side of the bore of the pipe and having at one side of the elbow 8 and at its outer end, an operating arm 12.

When the port 8^a is uncovered, the projection extends across the pipe 1; when the port is closed by the plate 10^a, the projection 10 lies at one side of the port and parallel with the axis of the pipe. A spring 13 surrounds the stud 11 and bears at one end against the plate 6 and its other end against a collar 12^a at the inner end of the lever 12 and holds the segmental plate 10^a to its seat.

16 A flexible pipe 14 is employed for the purpose of connecting the elbow 8 with the elbow 15 which projects from the inlet end of the heater proper. The elbow 15 is carried by a plate 16 which is provided at each 15 of its opposite ends with a pair of apertures 17, by means of which it may be secured to a flange 18 projecting from the inlet end of the said heater. It will be observed that this flange 18 is provided with a pair of 20 horizontally located apertures 19. The purpose of providing a single pair of horizontal apertures 19 while providing two pairs of diagonally disposed apertures in the flange 16 is to enable the heater to be reversed, 25 where necessary, and at the same time give a downward and forward inclination to the elbow 15, as will be explained more fully hereinafter.

The heater to which the heating fluid may 30 be supplied through the valve and connections above described comprises two groups of tubes, three such tubes 20 being shown in each group. The inlet ends of these tubes are all connected with a common header 21 which carries at its outer end the flange 18. Each group of tubes is connected at its opposite ends with a header 22, the two headers 22 being provided with a common exhaust pipe 23 provided with a flange 24. 40 The tubes 20 will be made of material which is thin and of high heat-conductivity while the headers 21, 22 and tube 23 may be made of relatively low heat-conductivity, such as aluminum, and the heater will be produced 45 by casting the headers around the ends of the tubes 20. This produces the heater in a particularly economical manner and at the same time secures a particularly strong and tight connection between the headers 50 and the ends of the tubes. The flange 24 is provided for the purpose of securing thereto the discharge connection 25. This discharge connection is flattened to reduce and widen the outlet 26 and is arranged to point downwardly, as shown in Fig. 2. The construction of the heater and the provision of this outlet provides, in effect, a muffler, in addition to a heater, whereby the gases exhausted through the heater and outlet pipe 23 55 and connection 25 will be discharged noiselessly.

The heater proper is mounted within a box-like casing 27, said casing comprising sides 28 and a bottom 29 having a central opening provided with a plate 30 pivoted

at one side thereof, as shown at 31, and retained in place by means of a pin or screw 33 received in a slot 32.

The side walls 28 may be double, as shown, whereby vertical spaces 28^a are provided for the supply of cold air beneath the tubes 20, which air is heated by the tubes and discharged through the openings in the open-work cover 34 which is secured to and completes the casing.

75 The flexible pipe 14 is necessarily of high heat-resisting material and comprises a main body 14^a composed principally of asbestos and having inside of the same a flat spiral 14^b, preferably of steel, and on its 80 outside a spirally wound wire 14^c.

The end of the arm 12 is connected by a link 35 with a lever 36, which bears at its upper end a gear segment 37 meshing with a rock 38 provided in the frame, which 85 frame is slidably mounted on studs 39 projecting from an end of the casing 27. This frame is provided with an elongated central opening 40 which is adapted to receive the inner end of the elbow 15 and to slide 90 transversely of the same and is also provided with a corrugated or roughened projection 41 above the cover plate. This particular construction does not constitute, in its details, a part of the invention of this 95 application, the same being shown and described in my Patent Number 996,130 issued June 27, 1911.

Reference has been made to the reversibility of the heater. The necessity for such 100 reversibility arises from the fact that, in some vehicles, the pipe 1 extends along the right-hand side of the vehicle while, in other vehicles, it will extend along the left-hand side. In order to reverse the heater herein 105 shown for connection with a pipe at the left-hand side of the vehicle, it will be necessary to reverse the casing 27, as the opposite ends are not identical, one of such ends being provided with a central single seat for 110 the inlet connection 18 and the other being provided with a pair of separated seats for the outer ends of the headers 22. For the purpose of inserting and retaining the heater in place, the cover 34 will be provided 115 at one end with a single depending projection 34^a having a semi-circular recess in the bottom thereof for the inlet connection 18 while the opposite end of the cover will be provided with a pair of such projections 34^b adapted to rest upon the upper surfaces of the headers 22, the ends of the casing 27 being cut away from the upper end thereof to receive such extensions. In 120 reversing the heater, it will be necessary to reverse the entire casing and to reverse the heater in the casing so that what was formerly the top of the heater will be the bottom. The elbow 15 will now, however, project forwardly and upwardly. In order 125 130

that the elbow may project forwardly and downwardly I make use of the other set of diagonally disposed openings 17 employed for the purpose of connecting the elbow to the flange. The pipe 23 now projects rearwardly, but the discharge end 25 projects upwardly instead of downwardly. Accordingly, all that it is necessary to do is to remove the discharge end, give it a half turn and secure it in place to the flange 24.

It will be observed that the valve projection 10 extends about half way across the pipe 1. This deflects a part only of the fluid into the elbow 8, leaving the rest to pass into the muffler. It will also be observed that, as the valve is rotated on its pivot 11 toward its closed position, the projection will intercept a progressively smaller proportion of the fluid passing through the pipe, the fluid intercepted being proportional to the exposed area of the elbow inlet 8 beneath the plate 10. Furthermore, the construction of the heater enables the exhaust gases to be handled quickly and to be discharged in a continuous stream through the outlet, the arrangement of the tubes 20 and the headers 21, 22 and discharge tube 23 securing this result.

Having thus described my invention, what I claim is:

1. The combination, with a motor exhaust pipe, of a heater, and means for supplying a portion of the gases in said pipe to said heater, said means comprising a conduit connecting the heater and the exhaust pipe, a plate pivotally supported adjacent to the junction of the conduit and the exhaust pipe and adapted by its rotation to control the conduit inlet, and a member projecting from said plate partly across the bore of the exhaust pipe and arranged to deflect a portion of the exhaust gases passing therethrough into the conduit.

2. The combination, with a motor exhaust pipe, of a heater, a conduit connecting the heater and the exhaust pipe, a plate pivoted adjacent to the junction of the conduit and the exhaust pipe and arranged by its rotation to cover and uncover the inlet end of the conduit, and a projection carried by said plate and extending partly across the bore of the exhaust pipe and arranged to deflect a portion of the exhaust gases in said pipe into the conduit, the valve and plate being so arranged that the gases thus deflected will be substantially proportionate to the area of the conduit inlet as regulated by said plate.

3. The combination, with a fluid supply pipe, of a heater, a conduit connecting the heater and the supply pipe, a valve regulating the effective area of the conduit inlet, and a projection carried by said valve and arranged to deflect a part of the fluid in the

supply pipe into the conduit inlet, the parts being so arranged and proportioned that the fluid thus deflected will be substantially proportionate to the area of the conduit inlet as regulated by said valve.

4. The combination, with a motor exhaust pipe, of a heater, a frame applied to the pipe and having a plate, the pipe being cut away within the frame to provide an opening presented toward said plate, a conduit extending from said plate to the heater, and a valve for deflecting into said conduit a portion of the gases flowing through said pipe, said valve comprising a segmental plate adapted to rest on the former plate and be swung across the conduit inlet, and a projection carried by said plate adjacent to the conduit inlet and extending partly duit extending from said elbow to the pipe.

5. The combination, with an exhaust pipe and a heater adapted to be mounted on either side of said exhaust pipe, of an elbow adapted to be applied to said heater and having a flange provided with two pairs of apertures, said heater having a flange for the reception of the former flange and provided with a single set of apertures arranged to register with either pair of the former apertures according to the position of the heater with respect to the exhaust pipe, means for securing said elbow flange to said heater flange with either set of apertures of the one flange in register with the apertures of the other flange, and a conduit extending from said elbow to the pipe.

6. The combination, with a motor exhaust pipe, of a heater adapted to be positioned on either side of said exhaust pipe and having an inlet and a tubular exhaust pipe, the inlet having an elbow, a conduit connecting said elbow with the motor exhaust pipe, means for varying the angle at which the elbow projects from the inlet, the heater exhaust pipe being provided with a flanged end and inclined discharge outlet having a flange, and connections for reversibly connecting the flange of the outlet to the flanged end of the exhaust pipe, whereby the heater may be inverted.

7. The combination, with a motor exhaust pipe, of a reversible radiator having an inlet end and an outlet end, an elbow connected to the inlet end, means whereby the angular relation of the elbow to the inlet end may be changed, a conduit connecting said elbow with the exhaust pipe, a discharge pipe connected to the opposite end of the radiator, said pipe having an outlet end, and means whereby the direction of the outlet end of said pipe may be changed to permit the reversal of the radiator without changing the direction of the discharge gases therefrom.

8. The combination, with a motor exhaust pipe, of a reversible radiator having an in-

let end and an outlet end, an elbow connected to the inlet end, means whereby the angular relation of the elbow to the inlet end may be changed, a conduit connecting said elbow 5 with the exhaust pipe, a downwardly directed discharge outlet for the outlet end of the radiator, and means whereby the direction of the outlet end may be changed to permit the reversal of the radiator without interfering with the downward discharge of 10 the gases through such outlet end.

9. The combination, with a motor exhaust pipe, of a reversible radiator having an inlet end and an outlet end, an elbow connected to the inlet end, means whereby the an- 15

gular relation of the elbow to the inlet end may be changed, a flexible conduit connecting the exhaust pipe with said elbow, a downwardly directed discharge outlet for the exhaust end of the radiator, and means 20 whereby said outlet end may be changed to cause a downward discharge of the gases therefrom when the radiator is reversed.

In testimony whereof, I hereunto affix my signature in the presence of two witnesses. 25

It is hereby certified that in Letters Patent No. 1,148,617, granted August 3, 1915, upon the application of Clyde S. Pelton, of Akron, Ohio, for an improvement in "Motor-Car Heaters," an error appears in the printed specification requiring correction as follows: Page 3, claim 4, strike out line 84 and insert the words and period *across the bore of the exhaust pipe.*; and that the said Letters Patent should be read with this correction therein that the same may conform to the record of the case in the Patent Office.

Signed and sealed this 7th day of October, A. D., 1919.

[SEAL.]

M. H. COULSTON,

Cl. 237—21.

Acting Commissioner of Patents.
